APPARATUS FOR APPLYING CENTER SPOTS
TO CROWN CAP CUSHIONSGunner Frederik Marinus Pedersen, Copenhagen,
Denmark, assignor to Dansk Crown-Cork
Fabrik ved Aage Weybye-Lassen, Copenhagen,
DenmarkApplication September 9, 1939, Serial No. 294,132
In Denmark March 1, 1937

2 Claims. (Cl. 113—80)

The invention relates to a machine for the manufacture of bottle caps or capsules of the kind consisting of a metal hood in which a tightening disc is inserted, and on the latter again a special round blank which ordinarily consists of metal foil, or other suitable sheet material. According to present practices these blanks are pressed down into the tightening disc, and are held in position there, for instance by some adhesive substance applied to the bottom side of the blank, or in that the tightening disc is given an incision into which a preformed edge of the blank can enter.

My present invention however, relates to a machine for attaching such round blanks in the tightening disc, without preforming the edge of said blank as heretofore, and the invention has for its object to stamp, in one working stage, the blank from a strip or sheet of metal foil, or other suitable sheet material, and depress or cut an edge into the tightening disc which previously has been deposited in the capsule, then to depress the blank into the incision so produced, and to maintain the blank in the depressed position, while the cutter is raised somewhat from the top face of the tightening disc, and at the time to exert a pressure on the centre of the tightening disc which pressure produces a stress in the material causing the originally cylindrical cut now to have an inward bent edge, by which means the blank will be retained in position, when also the piston commences to ascend, after the cutter has been raised somewhat.

By the descent of the piston, the tightening disc 20 will become crushed or permanently deformed, the outer edge of the depression becoming somewhat inclined, i. e. shaped about like a truncated cone so as to maintain the blank in position, while the central part of the tightening disc will be shaped according to the bottom surface of the piston.

One construction of the invention is shown on the drawing in which

Fig. 1 shows the machine in side elevation, partly in section,

Fig. 2 the same in front elevation,

Fig. 3 a section, to a larger scale, of the cutter and piston of the machine, in their position just above the strip of metal foil, or other suitable sheet or strip material,

Fig. 4 sections, similarly to a larger scale, of the cutter and the piston, in their lower extreme position.

Fig. 5 the position of the cutter and the piston in which the cutter is raised slightly from the

tightening disc, while the piston is still resting on the round blank, and

Fig. 6 the finished crown-cork.

On the drawing, all the parts not needed for understanding the invention are omitted. 1 is the base plate of the machine, 2 a post, 3 a bracket forming bearings for two double-armed levers 4, 5 and 6, 7, the free ends 4 and 6 of which are interconnected by means of a rod 8, 10 the lower pivoted connection of which to the arm 6 allows a certain play, for instance in that the hole 10 serving to co-operate with the pivot pin 9 of the arm 6 is oblong. Further, the part of the arm 6 that is outside of its pivot pin 11 15 is shorter than the corresponding part of the arm 4, 5 which is pivoted about a pin 12.

In the post 2 on the base plate 1, a cutter 14, mounted in a head 22, is adapted to slide vertically which cutter is connected at the top of the head 22 by means of a link 23 to the arm 5 and, at the bottom, has a circular cutting edge 15. Further, the cutter 14 is hollow, and encircles a piston 16 which receives a motion, independent of the cutter 14, in that the piston is linked to the arm 7. Besides, a small helical spring 17 is inserted between the cutter and the piston.

Below the cutter and the piston travels a strip 18 of a suitable sheet material, for instance metal foil, paper or the like, see Figs. 3, 4 and 5, from which the blanks are cut, in that the cutting edge 15 of the cutter passes through a bottom plate 19 below which a metal cap or capsule 21, fitted previously with a tightening disc 20 of cork or other suitable material, is disposed and mechanically guided in such a manner that the blank will be attached to the cork disc 20, exactly at the centre of the latter. The tightening disc 20, above referred to, is sometimes spoken of as a cork seal or liner.

The machine acts in the following manner:

A strip of metal foil, paper or the like is preferably introduced automatically by a feeding mechanism which is not shown on the drawing, and does not form any part of the invention. 45 The strip 18 is moved along the top surface of the bottom plate 19, and the cap or capsules 21 with the tightening discs 20 inserted therein, are similarly introduced automatically, in such a manner that whenever the cutter 14 and the piston 16 descend, a capsule will be situated accurately below the hole in the bottom plate 19.

When now the cutter and the piston descend, the edge 15 of the cutter 14 will produce a blank or slot 24 which will be sheared or stamped out,

when the cutter passes the bottom plate, and will be carried down to the tightening disc 20 of the capsule by means of both the cutter and piston acting as a unit, as shown in the drawing.

5 The cutting edge 15 of the cutter 14 will now penetrate down into the tightening disc 20, and will produce in the same a V-shaped circular incision with a vertical outer wall and inclined inner wall. The stamped blank 24 which is of 10 exactly the same diameter as the cutting edge, and being supported over the entire upper surface thereof, by the cutter and piston, as shown in Figure 4, will therefore fit accurately in the incision. When then the cutter 14 is raised, the 15 piston 16 will not commence to ascend simultaneously with the cutter 14, but owing to the slot 10 the piston 16 will not commence its ascent until the cutter 14 has been raised above the tightening disc, and by the pressure exerted by 20 the piston 16 the disc will expand somewhat, in such a manner that the vertical outer wall of the incision will now become inclined inward, and will maintain the edge of the blank in position.

From Figure 5 of the drawing, it will be seen 25 how the piston 19 remains in contact with the central surface of the disc 20 after the cutter 14 and piston 16 have simultaneously cut the disc and positioned the blank therein as shown in Figure 4. Thereafter the piston 16 presses the 30 blank and the portion of the disc in contact therewith into a plane below that occupied originally by the surface of said disc. By a comparison of the shape of the outer wall of the disc 20 as shown in Figure 5 with the shape of the 35 same as shown in Figure 4, the extent to which the disc 20 is crushed and expanded and the outer wall of the incision is inclined inwardly, becomes apparent. Now when the piston 19 is elevated from the position shown in Figure 5 and 40 the spot or blank is finally attached to the disc 20 in accordance with the teachings of my invention, as shown in Figure 6, it will be seen that the central portion of the disc 20 has been permanently depressed and that the exposed or 45 upper surfaces of both the blank and that portion of the disc surrounding the same are disposed in substantially the same plane.

While normally it will not be necessary to use a cementing of the blank to the tightening disc, 50 it may be preferable to employ a suitable adhesive substance, when discs of certain materials are used.

Having now described my invention what I claim as new and desire to secure by Letters 55 Patent is:

1. In a machine for attaching round blanks to bottle caps having disposed therein a tightening disc, punch means for stamping blanks from strip material; said punch means comprising a hollow 60 cylinder having a circular cutting edge, a circular piston movably mounted within said cylinder in axial alignment therewith, said piston having a

head adapted normally to fit within the cylinder with the cutting edge thereof projecting below said head, and die means through which said cylinder and piston as a unit is adapted to move vertically downwardly and cut round blanks from sheet material, means for supporting a bottle cap having a tightening disc disposed therein below said die means and in axial alignment with said cylinder, in combination with mechanism for operating said cylinder and piston as a unit to cut a blank from material disposed below said cylinder and piston and thereafter simultaneously make a circular incision in the tightening disc of the bottle cap and press said blank into said incision and into engagement with said disc, said mechanism comprising means for successively withdrawing said cylinder and piston from engagement with said blank and tightening disc, whereby said piston pressably dwells upon said blank and disc after the cutting edge of the cylinder has been withdrawn therefrom to deform the material of said disc and cause the same to retain the blank therein.

2. In a machine for attaching round blanks to bottle caps having disposed therein a tightening disc, annular cutter means for stamping blanks from strip material; said cutter means comprising a hollow cylinder having a circular cutting edge of V-shaped cross-section, a circular piston movably mounted within said cylinder in axial alignment therewith, said piston having a head shaped like a truncated cone and adapted normally to fit within the cylinder with the cutting edge thereof projecting below said head, and a bottom plate forming an opening through which said cylinder and piston as a unit is adapted to move vertically downwardly, said plate having a passage disposed transversely of said opening to receive strip material from which round blanks are adapted to be cut upon the downward movement of said cylinder and piston; and means for supporting a bottle cap with a tightening disc disposed therein below said bottom plate and in axial alignment with said opening, in combination with mechanism for forcing said cylinder and piston as a unit through the opening in said bottom plate to cut a blank from material disposed in the passage of said bottom plate and thereafter simultaneously make a circular incision in the tightening disc having a vertical outer wall and an inclined inner wall and press said blank into said incision and into engagement with said disc, said mechanism comprising means for successively withdrawing said cylinder and piston from engagement with said blank and tightening disc, whereby said piston pressably dwells upon said blank and disc after the cutting edge of the cylinder has been withdrawn therefrom to deform the material of said disc and cause the vertical outer wall of said incision to be inclined inwardly to retain the blank therein.

GUNNER FREDERIK MARINUS PEDERSEN.
